(57) **CLAIM**

The ornamental design for an aircraft, as shown and described.

DESCRIPTION

FIG. 1 is a top view of an aircraft showing our new design; FIG. 2 is a bottom view thereof; FIG. 3 is a side view thereof; FIG. 4 is a side view thereof; FIG. 5 is an enlarged view of FIG. 3, with environment removed for clarity of disclosure; FIG. 6 is an enlarged view of FIG. 4, with environment removed for clarity of disclosure; and, FIG. 7 is an enlarged view of a portion of FIGS. 4-6, with environment removed for clarity of disclosure. The broken lines illustrate environmental subject matter only and form no part of the claimed design; The broken lines surrounding the detail views labeled FIG. 7 are for annotation purposes only and form no part thereof.

1 Claim, 3 Drawing Sheets---
